(57) **CLAIM**

The ornamental design for a non-adhesive identification label, as shown and described.

DESCRIPTION

FIG. 1 is a perspective view of a non-adhesive identification label showing my new design in use;

FIG. 2 is a top plan view thereof, the bottom plan view being a mirror image;

FIG. 3 is a right side elevation thereof, the left side elevation being a mirror image; and,

FIG. 4 is a right end elevation thereof, the left end elevation being a mirror image.

The features shown in broken lines in FIG. 1 denote the nature and environmental use of the design and are not part of the claimed design.

The break lines indicate no specific length or width.
